BOTTLE CARRIER

Samuel N. Lebold, Chicago, Ill., assignor to Morris Paper Mills, Chicago, Ill., a corporation of Illinois

Original application June 14, 1946, Serial No. 676,787. Divided and this application May 20, 1948, Serial No. 28,188

3 Claims. (CL 224—45.1)

1

The present application is a division of my pending application, Serial No. 676,787, filed June 14, 1946.

This invention relates to improvements in a bottle carrier or package of the type employed in transporting a number of beverage bottles to and from a store. More particularly, the invention concerns a novel combination of such a carrier and a special suspending handle therefor, and details of construction of the handle itself.

It is an object of the invention to provide a carrier for a predetermined number of bottles of uniform size, all supported within the peripheral walls of the container on either side of a medial partition panel of the latter, and a suspending handle associated with said partition in a novel manner enabling a substantial decrease in the vertical dimension of the partition, while still permitting the carrier and contents to be comfortably and conveniently suspended in the hand in use.

A further object is to provide a combined carrier and separate removable handle therefor characterized by the ease and speed with which the handle may be associated with the carrier, said handle and carrier having coacting provisions enabling the handle to be supported either in an upright, fully elevated, carrying position, or in an inoperative withdrawn position beneath the upper level of the bottles permitting a number of filled carriers to be stacked vertically upon one another and in side-by-side contacting relation.

Yet another object is to provide a combined handle and a carrier of paper board construction in which the carrier is fabricated from a minimum of stock, being characterized by a medial suspending and partition panel terminating not higher than the top of articles contained therein, said handle in operative position projecting above the top of said panel for convenient grasping and transporting of the carrier.

Another object is to provide a novel carrier and handle combination in which the carrier and handle coact to support the handle in an erect, elevated position in vertical alignment with said partition and to enable depression of said handle to an inoperative position for stacking of the loaded carriers.

A still further object is to provide a handle of the type described which is constructed and arranged with particular relation to the lateral dimension of a bottle carrier and the bottles therein to enable retraction of the handle to an inopera-

2

tive position within the lateral limits of the carrier.

A still further object is to provide a suspending handle for association with a carrier of the foregoing central panel type, which handle is adapted to suspend the carrier at said panel and has provision for engaging said panel when shifted downwardly from its suspending position, whereby to continue to sustain the handle in vertically aligned relation to said panel.

The foregoing statements are generally indicative of the nature of the invention, but other and more specific objects will be apparent to those skilled in the art upon a full understanding of the construction and operation of the device.

Two embodiments of the invention are presented herein for purpose of exemplification, but it will be appreciated that the invention is susceptible of incorporation in other modified forms coming equally within the scope of the appended claims.

In the drawings,

Fig. 1 is a perspective view illustrating a handle and carrier construction according to the invention, in which the handle is shown in position for transportation of the loaded carrier;

Fig. 2 is a side elevation illustrating the carrier of Fig. 1 with the handle in retracted position for stacking of the filled carriers;

Fig. 3 is a view in end elevation showing the handle in upright carrier loading position;

Fig. 4 is a side elevation illustrating the carrier and handle in the position of Fig. 3;

Fig. 5 is a perspective view illustrating a modification of the invention utilizing a metal handle of different type from that shown in Figs. 1-4;

Fig. 6 is a fragmentary side elevation showing the combination of Fig. 5 in a stacked relation of two carriers;

Fig. 7 is an end elevation illustrating, in solid and dotted lines, alternative positions of the handle of the embodiment of Figs. 5 and 6;

Fig. 8 is a side view of the handle of Figs. 5-7 in depressed carrier loading position; and

Fig. 9 is a top plan view illustrating the mode of assembling the handle of Figs. 5-8 to the carrier.

This invention relates in general to improvements in a bottle carrier of the type illustrated and described in my U. S. Patent No. 2,389,318, dated November 20, 1945, and in particular to an improved suspending handle for such a carrier. The patent referred to describes at considerable length the advantages of providing a medial suspending panel for a carrier of this sort, which

panel is proportioned and disposed to extend not higher than the top of bottles in the carrier. Briefly stated, a substantial saving in production cost is effected due to the economy of stock made possible by the feature; and it is possible to stack filled cartons one on top of the other in a vertically aligned, side-by-side arrangement, rather than the laterally staggered arrangement to which earlier cartons were restricted, by reason of their projecting handle. Moreover, it obviates weakening of the handle portion by bending the same over the tops of the closures of the bottles to enable vertical stacking (a pre-formed crease was commonly provided in the handle for this purpose). A marked improvement in strength and rigidity also results from the lowering of the point of suspension of the carrier.

All of these substantial advantages are retained in the present construction, which employs a separate, pre-formed grip member easily and quickly associated with the carrier and extending thereabove to a conveniently accessible height for grasping. As an additional feature, said handle is readily and quickly retractable to an inoperative position beneath the level of the bottle caps, enabling the above referred to, vertically aligned stacking of filled carriers. It may also be sustained in vertical alignment with the central panel during loading of the carrier. Hence, when filled, the carrier presents an upstanding handle conveniently located for grasping and transportation.

The carrier of the present invention, generally designated by the reference numeral 10, is similar to that illustrated and described in the above identified patent. This carrier is of one-piece construction, comprising a bottom and parallel, bendably connected side walls 11 and end walls 12 fabricated from paper board stock. The construction of the carrier permits the use of a relatively light grade of stock, all as described in the patent above referred to, to which reference may be had for disclosure of these details. As also illustrated and described at length therein, the carrier is provided with a central, vertical partition and suspending panel 13 extending parallel to side walls 11 and bendably connected at its ends to the walls 12. Partition panel 13 is of double ply thickness (see Fig. 3) and extends upwardly to constitute a suspending handle member 14 which is likewise of double thickness. Transverse partition strips 15, integrally and bendably connected at their lateral extremities to the side walls 11 and partition panel 13, extend at right angles therebetween in a vertically staggered or stepped arrangement longitudinally of the carrier, to subdivide the space on either side of partition panel 13 into three equal sized, rectangular compartments 16. Each of these compartments is of a width generally corresponding to the maximum diameter of the bottles 17 disposed in the same, enabling insertion of the bottles bottom end first.

The suspending member 14 extends no higher than the upper level of the closures on bottles 17 in operative, supported disposition of said bottles in the carrier 10, and preferably lies somewhat below the tops of said bottles. This is of importance for the various reasons briefly referred to above. To particularize, in connection with the economy of stock which is realized, while the number of carton blanks that can be disposed laterally across a printing and/or cutting cylinder of, say, 70 inches diameter is more or less fixed, by reason of the standardization of cylin-

der lengths within certain limits, the number which can be arranged peripherally of the cylinder may be materially increased or diminished in accordance with the vertical dimension of the carton. Accordingly, it is apparent that a high suspending handle 14 would increase the manufacturing cost from the standpoints of output speed and cost of material. A plurality of cartons embodying the features of the patent, and also in accordance with this invention, may be stacked in direct vertical alignment, one on top of the other, with complete stability, as herein illustrated at Fig. 2. It is unnecessary to weaken any portion of the central panel 13, 14 by creasing, scoring or bending an upstanding end of the same to permit folding over onto the bottle tops for stacking. Other advantages of the arrangement will either be apparent to those skilled in the art or will be specifically alluded to in the description to follow.

In my patent referred to, the package shown and described is suspended by hand holes formed in the portion of the carrier corresponding to suspending handle 14, the knuckles of the user engaging the bottles and thrusting the same outwardly so as to effect a snug nesting of the user's hand therein. This results in a minimization of lateral instability and consequent wracking tendency, along with other advantages, all as pointed out in detail in the patent. These hand holes are retained in handle 14, being designated 14', so as to be available for use if desired. However, additional suspending means is also provided.

The suspending handle shown in Figs. 1-4 inclusive, and generally designated 18 is fabricated of a relatively light gauge sheet metal stock, stamped out in U-shaped outline to provide parallel vertical legs 19 and a connecting grip 20. The material of the grip is slotted adjacent the legs and upwardly curled at 21 for comfort in carrying. The lower termini of legs 20 are shaped in a generally triangular outline, as clearly illustrated in Fig. 3, including a bottom horizontal supporting reach 22 and an upwardly angled brace portion 23 converging toward the legs. Brace 23 is spaced somewhat from the adjacent leg 19 to enable initial insertion of the handle legs in elongated apertures 24 formed in the carrier panel 14. This spacing also permits the handle to be slid down on panel 14 until the horizontal supporting reaches 22 rest on the bottom of apertures 24, as clearly illustrated in Figs. 3 and 4, or even farther down if desired. Portions 23 and legs 19 then engage the opposite sides of panel 14 to sustain the handle 18 in an upright, but vertically lowered, position for loading of compartments 16.

When it is desired to stack a number of filled carriers, the handle is simply raised slightly from its position in Fig. 4 and swung laterally to the position illustrated in Fig. 2, in which it embraces the middle bottle of a row. The proportioning of the length of grip 20 is such as to permit the legs 19 to fall between the two end bottles and the length of the legs is less than the lateral dimension of compartments 16, whereby in the retracted position of the handle it lies entirely within the side limits of the carrier. Accordingly, the carriers can be stacked in rows in close side-by-side relationship without interference of any of the parts thereof. This form of handle is inexpensive and attractive in appearance and capable of repeated re-use.

A further variation of the inventive concept

is illustrated in Figs. 5-9 inclusive. Here a handle member 26 of U-shaped sheet metal construction is also employed, including spaced parallel legs 27 and a transverse grip 28. The legs 27 are spaced only sufficiently to provide a comfortable grip of the user at grip 28, enabling the handle to be swung laterally over the top of the middle bottle 17 and between the adjacent surfaces of the end bottles, as in the form of Figs. 1-5 inclusive, to a position beneath the tops of the bottles. This permits the vertical stacking referred to, illustrated in Fig. 6 and in dotted line in Fig. 7. Similarly, the overall length of the legs 27 and grip member 28 is such that in no position of the handle does it project laterally beyond the side walls 11. Provision is thereby made for the side-by-side stacking of the cartons, without interference during handling by automatic machinery, shipping or storage.

As particularly illustrated in Figs. 8 and 9, the legs 27 of handle 26 are shaped at the ends thereof by bending laterally and upwardly, so as to provide the out-turned hooked feet 29. Reference to Fig. 9 indicates that these feet extend a substantial distance laterally from the main body of the handle and legs thereof, and, moreover, that they are of a width lengthwise of the handle substantially equal to the width of legs 27. This feature provides a wide, non-linear bearing area of substantial length for engagement with the material at the upper margin of the openings 24 in panel 14, thereby reducing to a minimum the cutting or tearing action at the points referred to. Similar insurance against damage by cutting is afforded by the elongated line contact between handle and carrier in the preceding embodiment, shown in Figs. 1-5.

The feet 29 terminate in mutually in-turned toes or lugs 30 which are insertable in the openings 24 to place the handle in operative position on the carrier. In preferred form, the distance between the adjacent inner margins of openings 24 is less than the distance between the lugs 30, it being intended that the carrier 10, in a flat, collapsed form and prior to insertion of the bottles, be flexed (as shown in Fig. 9) along central vertical line to enable said lugs 30 to be inserted in the openings 24. Thereafter the carrier is allowed to return to its flat condition, with the feet 29 of the handle fully engaged in the openings, and bottles 17 loaded therein as illustrated in Fig. 5. Thus inadvertent displacement of the handle is impossible.

In use, the carrier and contents are suspended by the user in the manner illustrated in Fig. 7. If it is desired to stack a plurality of carriers on one another for transportation, storage or display, the handle is swung to the inoperative, laterally withdrawn position illustrated in Fig. 6 and in dotted lines in Fig. 7.

For convenience in filling the carrier 10 with bottles, I provide the handle legs 27 with integral struck-out stop lugs 31 on the same side as the feet 29 whereby, when it is desired to fill the carrier, the handle is merely slidably dropped down to the position illustrated in Fig. 8. In this position the stops 31 engage the top margin of the panel 14 and the feet 29 pass downwardly through openings 24 the necessary distance to permit such engagement. As shown in Fig. 7, the legs 27 and stops 31 have lateral restraining engagement with opposite sides of panel 14 to hold handle 26 vertically upright and aligned with panel 14. Thus positioned, the handle is imme-

diately accessible for lifting of the carrier when the latter has been filled.

Various other modified constructions of a handle adapted for connection to the suspending panel 14 of the carrier illustrated or to a similar member on a related type of carton will readily suggest themselves to those skilled in the art. It is appreciated that the handle may be fabricated of many different materials and I therefore desire that the invention be not unduly construed in this regard. Likewise, while particularly adapted for association with a bottle carrier such as shown in the above identified patent, its utility in connection with other types of cartons is apparent. Regardless of its particular form, the present construction provides a package of highly compact and economical character, including a carrier and associated handle capable of being comfortably transported by the user, and proof against destructive action between handle and carrier when so used, the handle being quickly and easily positionable in any desired relation to its associated carrier, depending upon the operation which is to be performed. All of the benefits characterizing the depressed central panel which are outlined above and in the referred to patent are retained in the present structure.

In both forms of the invention shown herein, the slotted hand holes 14', of the type shown in the above identified patent, are preferably retained in the central suspending portion 14 of the carrier. Thus, if it is not desired to employ the separate handle contemplated by this invention, or if such handles are not available, the user still has the means to get a firm and comfortable grip on the carrier to transport the same as described in the aforesaid patent.

I claim:

1. A suspending member for a flexible, a carton-like paper board bottle carrier of the type having a suspending panel internally subdividing the same, comprising a relatively rigid, pre-formed handle of generally U-shaped outline including a grip portion and generally coplanar legs on either side thereof, said legs having elements offset laterally from the plane thereof which are vertically engageable with said panel to suspend the carrier, in which position said handle is disposed along and generally parallel to a side of said panel, and further portions integral with and laterally spaced from said legs which are engageable with the opposite side of said panel for coaction with said legs to laterally support said handle in said generally parallel relation when in a depressed, non-suspending position.

2. A suspending member for a flexible, carton-like paper board bottle carrier or like container of the type having a suspending panel internally subdividing the same, comprising a relatively rigid, pre-formed handle of generally U-shaped outline including a grip portion and straight, downwardly extending, generally coplanar legs on either side thereof, said legs having elements offset laterally from the plane thereof which are vertically engageable with said panel to suspend the carrier, in which position said legs are disposed along and generally parallel to a side of said panel, said offset elements having upwardly extending portions disposed on the opposite side of said panel, said upwardly extending portions terminating in portions which are directed inwardly toward said legs and which are engageable with said opposite side of said panel for coaction with said legs to laterally support

said handle in said generally parallel relation when in a depressed, non-suspending position.

3. A suspending member for a flexible, carton-like paper board bottle carrier of the type having a suspending panel internally subdividing the same, comprising a relatively rigid, pre-formed handle of generally U-shaped outline including a grip portion and generally coplanar legs on either side thereof, said legs having elements offset laterally from the plane thereof which are vertically engageable with said panel to suspend the carrier, in which position said handle is disposed along and generally parallel to a side of said panel, and further portions integral with and laterally spaced from said legs which are 15 engageable with the opposite side of said panel

for coaction with said legs to laterally support said handle in said generally parallel relation when in a depressed, non-suspending position, said further portions being formed in said legs between said grip portion and offset elements.
